Cl. Foster

Attorney

UNITED STATES PATENT OFFICE.

SARAH N. LEOPARD, OF ATLANTA, GEORGIA.

APPAREL.

1,341,716.

Specification of Letters Patent. Patented June 1, 1920.

Application filed June 12, 1919. Serial No. 303,650.

To all whom it may concern:

Be it known that I, SARAH N. LEOPARD, a citizen of the United States, residing at Atlanta, in the county of Fulton and State of Georgia, have invented certain new and useful Improvements in Apparel, of which the following is a specification.

The present invention relates to feminine wearing apparel, and more particularly to undergarments.

10 The object is to provide a combination body garment that will properly maintain its position on the wearer, and will eliminate the expense of a plurality of sets of 15 trimmings and the unsatisfactory and unsightly plurality of sets of supporting shoulder straps, at the same time providing a garment that is entirely practical, convenient, and one that can be made as plain 20 or as ornamental as desired.

In the accompanying drawings:—

Figure 1 is a perspective view of the combination garment, indicating the same on a wearer.

25 Fig. 2 is a longitudinal sectional view therethrough.

Similar reference numerals designate corresponding parts in all the figures of the drawings.

30 In the present invention, the undergarment is designated 3, and is a combined undershirt or undervest and drawers, the latter preferably being substantially legless, and made of any desired material and pattern.

35 Surrounding the upper portion thereof is a corset cover garment or camisole, designated 4, which may be as plain or as elaborate as desired. These two garments are 40 united at their upper ends as shown at 5, preferably by stitching the same together. The lower portion of the outer garment 4 preferably terminates substantially at the 45 waist line and is entirely free of the undergarment. Extending above the line of connection 5 between the garments is a section 6 that is common to both and may be as plain or as ornamentally trimmed as desired. A single set of shoulder straps 7 is 50 connected to this section or trimming and constitutes supporting means for both garments.

In order that the upper portion of the combination garment may be properly fitted 55 to the wearer, means are provided for con-

tracting the same, said means being preferably a drawstring or ribbon 8 that is located in the trimming at or near the upper edge of section 6. Means are also provided for contracting the lower portion of the corset 60 cover or camisole substantially at the waist line, this means in the present embodiment being shown as a drawstring or ribbon 9 slidably mounted in the lower portion of the outer garment 4.

65 It will be clear that this article of manufacture is one that can be easily applied to and removed from the wearer, providing a comfortable garment that will maintain at all times its proper position. A single set 70 of shoulder straps serves to support both garments, and the trimming is common to both, thereby materially reducing the cost. The means 8—9 serve to properly fit both garments to the wearer, and it will be obvious that the outer garment by reason of its attachment solely at the top, will permit the corset to be placed in position and removed with ease. In connection with this combination garment, a brassière may be worn if desired. This brassière may be interposed between the two and detachably secured or mounted by any suitable means, or in any manner desired, or if preferred may be worn beneath the undervest.

80 From the foregoing, it is thought that the construction, operation and many advantages of the herein described invention will be apparent to those skilled in the art, without further description, and it will be understood that various changes in the size, shape, proportion and minor details of construction, may be resorted to without departing from the spirit or sacrificing any of 85 the advantages of the invention.

Having thus fully described my invention, what I claim as new, and desire to secure by Letters Patent is:—

90 Apparel of the character set forth, comprising a loose body covering under-garment adapted to extend from the bust to the legs, the lower end thereof being substantially tapered and closed at its apex with leg openings on opposite sides thereof, 95 a corset cover garment surrounding the upper portion and secured at its upper end to the upper end of the garment, common trimming for both garments extending above the line of connection of said garments, common shoulder straps for both 100

105

110

garments connected to the upper ends thereof, means carried by the lower portion of the corset cover garment to contract the same about the under garment substantially at the waist line of the wearer, and body encircling means substantially at the junction of the garments and independent of the shoulder straps and passing beneath the

arms of the wearer for contracting the said upper portion of the garment.

In testimony whereof, I affix my signature in the presence of two witnesses.

SARAH N. LEOPARD.
